UNITED STATES PATENT OFFICE

2,451,328

ULTRA HIGH FREQUENCY ELECTRON
DISCHARGE DEVICE

Christopher Henry Foulkes, London W. C. 2, England, assignor to Standard Telephones and Cables Limited, London, England, a British company

Application, September 9, 1942, Serial No. 457,795
In Great Britain February 14, 1941

Section 1, Public Law 690, August 8, 1946
Patent expires February 14, 1961

4 Claims. (Cl. 250—27.5)

1

This invention relates to electron discharge devices and more particularly to such devices of the kind embodying hollow resonators, as for example, electron discharge devices employing velocity modulation of an electron stream.

An object of the invention is the provision of a simple construction of resonator for such devices.

Another object of the invention is to provide a simple construction of such device in which the heat generated in the resonator is readily dissipated.

According to one aspect of the invention a resonator for an ultra high frequency electron discharge valve comprises an inner and an outer conductor in which the outer conductor consists of two or more channel-shaped sections welded or riveted together to form a tube.

According to another aspect of the invention in a coaxial resonator for electron velocity modulated valve the outer conductor comprises two channel-shaped sections preferably of semi-cylindrical shape provided with integral fins so shaped and located that when the sections are riveted or welded together the fins bound the longitudinal edges of a pair of diametrically-located slots in the wall of the resonator.

One embodiment of the manner in which the invention is carried out will be described with reference to an electron velocity-modulated device of the kind described in United States application No. 367,401 of November 27, 1940 now Patent No. 2,320,860 granted June 1, 1943 in which the hollow resonator comprises a short length of coaxial line.

In the accompanying drawings:

Figure 1 shows in perspective view a half-section of an outer conductor for a resonator;

Figure 2 is a perspective view of a complete outer conductor formed of two such half-sections;

Figure 3 is a perspective view of an anode;

Figure 4 is a perspective view of the assembled resonator tube and its associated socket;

Figure 5 is a vertical section through the centre of assembly and

Figure 6 is a plan of the base at a section taken on the line 6—6 of Figure 5.

The outer tube of the resonator instead of consisting of a copper tube as in the previous practice comprises two semi-cylindrical half-sections 1, 2 (Fig. 2) as shown in Figure 1 formed with lugs 3 and integral fins 4. The two sections, which may be pressed from sheet metal stampings, are riveted or welded together to form a complete tube 35 as shown in Figure 2, with

2

the fins 4 bounding the diametric apertures through which the electron beam is fired. An aperture 5 is provided in one section through which a loop or probe is inserted into the interior of the resonator for extracting high-frequency energy. Protruding lugs 6, 7 are provided at each end of the sections 1, 2 for securing mica insulators which carry the cathode, control grid and any further electrodes.

It will be appreciated that with this construction of resonator the fins 4 are integral with the main body of the resonator, whereas in the resonators previously formed from a section of copper tube they had to be separately provided and attached to the edges of the apertures. The present construction affords the advantage that heat is more readily conducted away from the fins.

It will, moreover, be seen that such a resonator 20 is provided with a slot or aperture at each side although it is only necessary to provide a slot at one side for ingress of the electron stream. Advantage is taken of the presence of two slots to employ at the side where the electrons emerge, 25 a curved molybdenum anode 8 of the shape shown in Figure 3. The majority of the electrons will pass right through the resonator and will bombard the anode 8, which, being of molybdenum, is able to dissipate heat at a higher temperature 30 than copper. More heat can accordingly be dissipated than would be possible in the copper tube, and the risk of distortion of the inner or outer conductor or both due to excessive heating of the copper is avoided.

The anode 8 is also provided with a small hole 35 through which a small proportion of the electron stream passes to a small collector electrode 24 shown in Figure 5. This electrode is used when aligning the tube with respect to the external magnetic field, the correct adjustment 40 being when a maximum current passes right through the small hole on to the collector electrode 24.

Figures 4 and 5 show how the resonator and 45 its associated electrodes are mounted so that its axis is parallel to the major axis of the enclosing bulb, on a base of the kind comprising a dished glass member 9, the peripheral lip of the member 9 being used to a lip on the lower end of the 50 enclosing glass bulb 10. Contact pins 11 are sealed directly into the dished member 9. The inner conductor of the resonator is made up of two copper rods 30 and 31, each having one end 55 spread out into a head of mushroom form. The small ends of the rods support an assembly of

fins 32 which defines the slot through which the electron stream is fired. The outer conductor 35 is fixed at both ends to the mushroom heads of the rods.

The resonator is mounted upon a triangular copper plate 12 by means of a copper rod, 25 screwed into the head of the rod 30, the washer 26 providing the necessary spacing. The plate 12 is spot welded to three of the base pins 11. This permits the resonator to be located near the base and assists in dispersing the heat which is generated. The triangular plate 12 also has cut in it three slots 27 with their lengths parallel to the respective sides as shown to enable the plate to take up any strains which may be caused by unequal expansion of the glass and copper. The anode 8, the collector plate 24, the grid 28 and the cathode 29 are mounted upon rods 13 which pass through the mica insulators 14 and 15 and through mica spacing plates 16. The remaining pins 11 in the base are used for connections to the electrodes.

A glass tube 17 is sealed into the bulb 10 adjacent the hole 5 in the resonator. Conductors 18 for extracting energy extend through the tube 17 and aperture 5, into the resonator, the conductors being sealed in a pinch 19.

When the valve is plugged into its socket 20, the three pins 11 which support the triangular platform or plate 12 engage in holes drilled in a substantial metal spider 21 fixed to the socket. The remaining pins engage contact terminals 22 on the socket in the usual manner. The socket 20 is provided with a central hole 33 having a key-way 34 into which the protruding metal spigot containing the sealing off tube of the glass bulb 10 extends. This spigot has a key which engages with the key-way 34 so as to ensure that the pins 11 make contact with the proper terminals 22 of the socket.

The invention is not limited to the precise construction described and modifications coming within the scope of the appended claims will occur to those versed in the art. For example, the outer conductor of the resonator may be built up from three or more curved sections of suitable shape.

What is claimed is:

1. A coaxial resonator for an electron velocity modulated discharge tube comprising an outer tubular conductor and an inner conductor coaxial therewith, said outer conductor being formed of integral channel-shaped sections secured together at their edges, said sections having inturned fins integral therewith and forming the longitudinal

boundaries of a pair of diametrically located slots in said outer conductor.

2. A hollow resonator for an electron velocity modulated discharge tube comprising channel-shaped sections secured together at their edges, said sections having similarly located inturned fins integral therewith and located at their edges and forming the longitudinal boundaries of a pair of diametrically located slots in said resonator.

3. An ultra high frequency discharge tube comprising a coaxial resonator formed of concentric inner and outer conductors, said outer conductor consisting of two channel-shaped sections secured together, similarly located fins on said sections forming the longitudinal boundaries of a pair of diametrically located slots in said outer conductor, and said inner conductor including rods supported from opposite ends of said outer conductor and extending to positions opposite the respective ends of said diametrically located slots and electrodes mounted adjacent said slots.

4. An electron velocity modulated discharge tube comprising channel-shaped sections secured together at their edges and forming the outer conductor of a coaxial resonator, said sections having similarly located inturned fins integral therewith and located at their edges and forming the longitudinal boundaries of a pair of diametrically located slots in said outer conductor, a conductor within and coaxially with said outer conductor, a cathode adjacent to one of said slots, and an anode adjacent to the other of said slots.

CHRISTOPHER HENRY FOULKES.
